SAFETY ATTACHMENT FOR SMOKERS' ASH RECEPTACLES

Frederick A. Nichols, Stratford, and
Donald H. Vero, Bridgeport, Conn.

Application April 28, 1951, Serial No. 223,474

5 Claims. (Cl. 131—240)

1

This invention relates to new and useful improvements in smokers' accessories and has particular relation to an ash receptacle including means to receive a lighted cigarette or cigar and prevent the same from burning down, overbalancing and falling from the receptacle onto a table or the floor, and which means is adapted when a lighted end of a cigar or cigarette approaches a predetermined position with respect to the means to tilt and feed the lighted cigar or cigarette forwardly inwardly over the receptacle and, in some instances, depending on the heat applied to the means by the burning cigar or cigarette, discharge the latter into the receptacle.

An object of the invention is to provide an ash receptacle having the characteristics described.

Another object is to provide an ash receptacle attachment which is easily and quickly applied to an ash receptacle and imparts thereto the characteristics outlined and which is readily applicable to various types or constructions of ash receptacles.

Another object is to provide an attachment for the purpose stated and which is of simple construction and easily assembled and wherein the attachment is not likely to be damaged while in a place of use.

Other objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a view partly in side elevation and partly in section and showing a portion of an ash receptacle having the invention incorporated therein;

Fig. 2 is a view similar to Fig. 1 but with the tray of the attachment in reverse position and over the receptacle;

Fig. 3 is a top plan view of Fig. 1; and

Fig. 4 is an exploded view showing disassembled the various parts of the present attachment.

Referring in detail to the drawing wherein the invention is shown as an attachment, complete in itself, for an ash receptacle, at 10 is generally indicated a portion of an ash receptacle of any suitable size and material and including an edge flange 11, the inner edge of which comprises a

portion of the vertical or upwardly directed side wall of receptacle 10. The ash receptacle 10 is merely shown to assist in an understanding of the application and operation of the invention, considered as a safety attachment for ash receptacles.

Such safety attachment, generally designated 12, is easily applied to and removed from any ash receptacle and as most clearly shown in Fig. 4, 10 comprises but four parts which may be easily and quickly assembled without the use of any special tools. Instead of having a complete attachment as herein shown, a portion of the invention may be incorporated in the receptacle itself.

15 Attachment 12 comprises a mounting means or base 13, shown as blanked and formed from a single piece of sheet metal although it may be otherwise made, as of plastic or the like, if desired. Base 13 includes an elongated body 14 having a hook 15 at the underside of its outer end. Such hook is formed by bending the outer portion of the body downwardly and then inwardly. At the inner end of the body, a short depending portion 16 attaches to the body a cross piece 17 located in a plane normal to that of the body. Cross piece 17 has its remote ends bent inwardly into substantially parallel relation providing a pair of ears 18 and 19 having non-circular openings, illustrated as comprising vertically extending slots 20, passing entirely therethrough.

In addition to the base 13, the attachment 12 includes a pivot member also shown alone in Fig. 4 and generally designated 21. This pivot member is formed from a piece of thin flat stock and 35 in addition to a body 22 includes end portions 23 and 24 of reduced width but still having flat sides and which end portions are of such size as to transversely fill the slots 20 through the ears 18 and 19, respectively, whereby the pivot member 30 may not rotate relative to base 13. Rather than make the pivot member 21 of a single piece of stock, it may be of laminated construction comprising two or more similarly shaped thin pieces 40 merely disposed in side-by-side contacting relation.

The third element of the safety attachment 12 is also shown alone in Fig. 4 and is generally designated 25. This element comprises a spiral spring body 26 formed from a strip of bimetal. 50 One extending end portion 27 of said strip is shown as slightly longer than the other end portion 28 thereof and the purpose of the bimetal spiral and the purpose of its construction will be set forth in connection with the assembled or completed attachment.

The fourth and last element of attachment 12 is a tray generally designated 29 and shown as made up of sheet metal comprising an upper wall 30 the mid portion of which is transversely curved to provide an elongated channel portion for the reception of a cigarette. Beyond the inner end of this mid portion, tray 29 includes extensions 31 and 32 which really comprise extensions of depending side wall portions 33 and 34. These extensions 31 and 32 are each provided with a round opening or perforation 35 and the openings or perforations are substantially aligned. At its outer end, the top wall 30 of the tray is extended providing an extended support 36 for a long or so-called "king size" cigarette.

In assembling the attachment from the elements described, the spiral 25 is slipped over the pivot member 21 from one end of the latter. The pivot member is of such less width than the internal diameter of the spiral body 26 that its upper edge engages the upper portion of the peripheral inner surface of the spiral body 26 and, as shown clearly in Figs. 1 and 2, the side surfaces and lower edge of the pivot member are out of contact with the spiral body. Thus, the spiral body is loosely supported on and about the pivot member, so that there is no restriction to its uniform expansion and contraction, and its substantial line contact support upon the upper edge of the pivot member prevents any appreciable dissipation of heat to the pivot member. Then the pivot member with the spiral 25 thereon is disposed between the extensions 31 and 32, the tray side wall portions 33 and 34 and the reduced end portions 23 and 24 of the pivot member are inserted into the perforations or openings 35 of the respective extensions.

At this time, spiral 25 is located in such manner that its longer arm 27 is disposed against the under side of the upper wall 30 of the tray, as in Fig. 1, and its shorter arm 28 is extending outwardly. Now the base 13 is applied by slipping its ears 18 and 19 over the ends of the pivot member 21, it being understood that the reduced portions 23 and 24 of said pivot member extend beyond the outer sides of the extensions 31 and 32 of the tray.

These extending portions of the pivot member are received in the slots 20 in the ears 18 and 19 of the base. The diameter of openings 35 is such that the tray is mounted for pivotal movement on the pivot member and the tray has a normal position extending over the body 14 of the base and, in fact, straddling such body with the side walls 33 and 34 of the tray beyond opposite edges of the body. Additionally, the tray is of such length as to extend beyond the outer downwardly bent or hook portion 15 of the base. Here it is noted that the side walls 33 and 34 of the tray are tapered longitudinally whereby normally the tray is at an incline of approximately 10 degrees, tending to cause an object placed thereon to move into the receptacle 10. Also, it is noted that the shorter arm 28 of coil 25 is now disposed on an upper side of the cross piece 17 of the base.

When the present attachment is to be used, it is merely necessary to slip its hook portion 15 over the outer edge of the flange 11 of the ash receptacle, the attachment at this time being at somewhat of an angle. Then the attachment is lowered into place with the body 14 of its base extending radially inwardly over the edge flange of the receptacle with the cross piece 17 and the pivot member 21 and the spiral 25 all located slightly inwardly of the receptacle flange 11 and

over the hollow portion of the receptacle. All this is as in Figs. 1 and 3. There it will be noted that the tray 29 has its upper wall 30 stopping outwardly of its extensions 31 and 32 and thus the spiral 25 is exposed at the inner end of the tray although in a position flush with or at the most but slightly below the level of the lowermost portion of the curved center portion of the tray.

At this time, the underside of the tray is engaged by the arm 27 of the spiral 25. When a lighted cigarette is placed on the tray with the ignited end of the cigarette inwardly or over the receptacle, the cigarette will be prevented from burning back and overbalancing and falling from the receptacle as onto the floor or onto a table supporting the receptacle. As the cigarette is consumed and its ignited or burning end approaches the spiral 25, heat is applied to the latter and the bimetal tends to distort in an unwinding action.

Since its end portion 28 is against the cross piece 17, such end portion may not move downwardly. However, its end portion 27 is also free merely bearing against the underside of the tray 29 and the latter is pivoted for movement on the extending end portions 23 and 24 of the pivot member 21. Thus, as heat is applied to the bimetal, its arm 27 presses upwardly on the tray moving the same from the full line position of Fig. 1 as to or toward the dotted line position thereof.

As the tray is so tilted, by gravitational movement, the cigarette will slide downwardly. In the case of a relatively short, or mostly consumed, cigarette having relatively little weight and frictional resistance it will usually slide entirely off the tray and into the receptacle 10 where the burning cigarette will do no real harm. In the case of a relatively long, or freshly lighted, cigarette having greater weight and frictional resistance, the burning cigarette moves intermittently only, its burning end moving inwardly from over the spiral 25. In such instance, the spiral will cool because of the remoteness of the burning end of the cigarette and the tray will move back to its normal position (full lines of Fig. 1) or back toward such position.

As the cigarette continues to burn, its ignited end approaches the spiral and the tray is again tilted to either have the cigarette slide off the tray into the receptacle or to have the cigarette slide inwardly on the tray carrying its burning end from the immediate vicinity of the spiral and, in the latter case, the above described cycle will be repeated.

With a rapidly burning cigarette, the tray may move not only upwardly to the dotted line position of Fig. 1, but may continue upwardly to and slightly past a vertical position, and in the latter instance, the tray drops forward as to the position of Fig. 2. However, this does not occur very frequently and the tray is shown in the mentioned position in Fig. 2 for the purpose of better illustrating the fact that the arms 27 and 28 of the spiral 25 are completely unattached and also for the purpose of illustrating the freedom of movement of the tray.

Attention is particularly directed to the fact that the arms of the spiral 25 are not attached either to the base 13, to the receptacle 10, or to the tray 29. One of them merely bears against an upper edge of a part of the base and therefore such arm cannot move downwardly and the other arm bears against the underside of the tray but

is not attached to it. Where the base 13 is omitted and the portions corresponding to ears 18 and 19 are made as part of the receptacle, the arm 28 of the spiral will bear on an upper edge portion of the receptacle.

Should the arms of the spiral be attached, the spiral will soon be distorted and be non-workable for the purpose intended, due to the fact that the device incites considerable curiosity on the part of those witnessing its operation and they, in turn, tend to raise the tray to see what is under it and in doing so, distort the bimetal whereupon the parts do not return to their proper positions. When the spiral 25 is distorted and its ends are attached, there is no freedom of movement of the tray and the distorted spring maintains the tray elevated and the entire device is rendered useless.

Attention is also especially called to the pivot member 21. This pivot member retains the spiral 25 in position flush with or only slightly below the plane of the upper surface of the curved portion of the tray and this is accomplished by having the spiral rest on the upper edge of the pivot member. In order to maintain the spiral in position, the pivot member is restrained from movement out of a position wherein the planes of its flat sides are substantially normal to the plane of the body 14. This is accomplished through the use of the flat sided slots 20 receiving the flat sided end portions 23 and 24 of the pivot member.

If the pivot member were permitted to turn through 90° the spiral would drop from its position a distance equal to nearly 1/2 the width of the pivot member and thus be remote from the plane of the cigarette receiving surface of the tray and not properly positioned to be affected by the heat from a burning cigarette. A round pivot member will not serve the present purpose since the mass of its metal absorbs a great deal of heat from the bimetal, the latter will not be sufficiently heated from the burning cigarette or will not retain such heat and transmit it about the spiral or along the spiral for the purpose of having the spiral function in the manner above described. The ears 18 and 19 serve merely as a mounting for the pivot member 21. Thus, while in an attachment these ears are shown as conveniently made part of the base 13, it will be clear that these ears can be formed otherwise, as elements or portions of the receptacle.

Having thus set forth the nature of our invention, what we claim is:

1. In a safety attachment for cigarette smokers' ash receptacles, a base including an upwardly facing abutment portion and a pair of spaced ears, a pivot member supported by said ears, a tray pivoted at its inner end on said pivot member for pivotal movement between a substantially horizontal position extending over said base and an inclined position at an angle to said base, a spiral comprising a strip of bimetal for moving said tray on its pivot from the first toward the second of its named positions when such spiral is heated, said spiral being loosely supported on and about said pivot member and having outwardly extending free end legs, one leg constituting an extension from one end of said spiral at the lower portion thereof, said leg extending over and against said abutment portion whereby said leg is limited in its downward movement and being free of connection with said abutment whereby it is free to move upwardly, and the other leg constituting an extension from the other end of said spiral at the upper portion

thereof, said other leg extending in lifting relation at the underside of said tray and being free of connection with said tray.

2. In a safety attachment for cigarette smokers' ash receptacles, a tray having an elongated cigarette supporting surface, a base member, pivot means carried by said base member pivotally mounting said tray for movement about a horizontal axis between a substantially horizontal cigarette supporting position and an inclined cigarette dumping position, a heat responsive cylindrical spiral comprising a strip of bimetal having its axis parallel to the pivot axis of said tray and having the upper portion of its peripheral outer surface substantially in the plane of and adjacent said cigarette supporting surface, said spiral having a leg constituting an extension from one end of said spiral and extending in lifting relation to said tray, said pivot means constituting a support means for said spiral and having an upwardly disposed edge portion in substantial proximity to said plane of said cigarette supporting surface, said spiral being loosely supported solely on and about said pivot member with only the upper portion of the spiral's peripheral inner surface in contact therewith along said upwardly disposed edge.

3. In a safety attachment for cigarette smokers' ash receptacles, a tray having an elongated cigarette supporting surface, a base member, pivot means carried by said base member pivotally mounting said tray at one end for movement about a horizontal axis between a substantially horizontal cigarette supporting position and an inclined cigarette dumping position, said horizontal axis being downwardly offset from the plane of said cigarette supporting surface, a heat responsive cylindrical spiral comprising a strip of bimetal having its axis parallel and substantially contiguous to the pivot axis of said tray and having the upper portion of its peripheral outer surface substantially in the plane of and adjacent said cigarette supporting surface, said spiral having a leg constituting an extension from one end of said spiral and extending in lifting relation to said tray, said pivot means constituting a support means for said spiral and having an upwardly disposed edge portion in substantial proximity to said plane of said cigarette supporting surface, said spiral being loosely supported on and about said pivot member with only the upper portion of its peripheral inner surface in contact therewith along said upwardly disposed edge.

4. In a safety attachment for cigarette smokers' ash receptacles, a tray having an elongated cigarette supporting surface, a base member, pivot means carried by said base member pivotally mounting said tray at one end for movement about a horizontal axis between a substantially horizontal cigarette supporting position and an inclined cigarette dumping position, said horizontal axis being downwardly offset from the plane of said cigarette supporting surface, a heat responsive cylindrical spiral comprising a strip of bimetal having its axis parallel and substantially contiguous to the pivot axis of said tray and having the upper portion of its peripheral outer surface substantially in the plane of and adjacent said cigarette supporting surface, said spiral having a leg constituting an extension from one end of said spiral and extending in lifting relation to said tray, said pivot means constituting a support means for said spiral and having a vertically elongated cross section having an up-

wardly disposed edge portion in substantial proximity to said plane of said cigarette supporting surface, said spiral being supported on and about said pivot member with the upper portion of its peripheral inner surface in contact therewith along said upwardly disposed edge.

5. In a safety attachment for cigarette smokers' ash receptacles, a tray having an elongated cigarette supporting surface, a base member, pivot means carried by said base member pivotally mounting said tray for movement about a horizontal axis between a substantially horizontal cigarette supporting position and an inclined cigarette dumping position, a heat responsive cylindrical spiral comprising a strip of bimetal having its axis parallel to the pivot axis of said tray and having the upper portion of its peripheral outer surface substantially in the plane of and adjacent said cigarette supporting surface, said spiral having a leg constituting an extension from one end of said spiral and extending in lifting relation to said tray, said pivot means constitut-

ing a support means for said spiral and an upwardly disposed edge portion in substantial proximity to said plane of said cigarette supporting surface, said spiral being loosely supported solely on and about said pivot member with only the upper portion of the spiral's peripheral inner surface in contact therewith along said upwardly disposed edge, said spiral having opposite ends thereof free of connection with any portion of the tray.
